UNITED STATES PATENT OFFICE.

ROBERT G. FLEMING, OF BLOOMFIELD, NEW JERSEY, ASSIGNOR TO SMOKADOR MANUFACTURING CO., INC., OF NEW YORK, N. Y., A CORPORATION OF DELAWARE.

ASH STAND.

Application filed December 22, 1926. Serial No. 156,444.

This invention relates to ash stands, and particularly to that type of stand that is supported upon the floor with the ash tray elevated to a point within convenient reach 5 of the user, said stand being so constructed that ashes, burnt matches, cigarette and cigar butts, and similar waste received by the tray, will be from thence conducted into a waste-receiving receptacle in the lower 10 part of the stand, wherein it will be accumulated and retained in a sanitary manner without contaminating the surrounding air with objectionable odors. One object is to provide means whereby the waste-receiving 15 receptacle may be readily detached for the purpose of emptying the contents, and thereafter attached in operative position with equal ease. The invention also aims at simplicity of construction, reduction in the 20 number of parts necessary to a complete stand, said parts being so constructed that they may be easily and quickly assembled. These and other objects will be apparent to those skilled in this art from a reading of 25 the following description and an examination of the accompanying drawings, in which—

Fig. 1 is a side elevation, partly broken away at the middle portion, and shown in 30 quarter section;

Fig. 2 is a similar view, illustrating a modification;

Fig. 3 is a sectional view on a relatively reduced scale of a part of the base, showing 35 a supplemental feature.

In Fig. 1, 6 represents an ash receiving tray having a waste discharge outlet in the lower part thereof. Depending from said tray is a waste conducting conduit 4 of 40 tubular form, the cross section of which may be round, as shown, or of any other well known shape. This conduit is sufficiently large to permit waste material, such as ashes, burnt matches, cigarette butts and the like to easily fall therethrough. In the particular form shown the lower end 7 of the tray is interlocked or otherwise properly secured to the upper end 5 of the waste conducting tube or conduit. At the upper edge 45 of the ash tray there may be formed a narrow annular platform 8 with a circular depending flange 9. Cigars, cigarettes and the like may rest on the platform 8 or may be held between suitable gripper jaws 11—11, 50 which may be provided as one effective

means for safely holding a lighted cigar or cigarette on the stand, 10 represents a match box holder, which may be mounted on the platform 8, if desired. 22 is what I may term a skirt member, which is secured at, 55 or adjacent to, the lower end of the conduit 4 and extends downwardly below the same, said connection preferably being rigid. This skirt is of a sufficient size and shape to form a relatively enlarged cavity below the lower 60 end of the conduit 4, said cavity being sufficiently large to wholly receive therein a removable waste-receiving receptacle 3, the same being insertible through the open lower 65 end of the skirt. This skirt extends sufficiently below the waste conducting conduit 70 so that it will rest on the floor or other support when in use. In the preferred construction the skirt is made of a single piece of metal, although, this, of course, is not essential. 17 is a socket carried by the lower 75 end of the conduit 4 into which the upper end 19 of the waste-receiving receptacle projects, when the parts are assembled, and with which it may be secured or interlocked 80 in any desired way, as by coacting threads formed on these parts respectively. The threaded parts are indicated at 18. 20 is a circumferential flange on the receptacle 3, while 21 is a gasket or packing washer which 85 may be employed, if desired, for the usual purpose between the flange 20 and the socket 17. It will be observed that the waste-receiving receptacle 3 is indicated as being 90 made of glass, and it is apparent at once that it is of the conventional shape of an ordinary fruit or preserve jar. Thus, the user may at any time readily observe to what extent the waste-receiving receptacle is loaded 95 with waste, by simply lifting the stand and peering through said glass receptacle. Again, if the user should have the misfortune to break the jar, it may be very readily replaced for a few cents, or without any expense if the user happens to have a similar 100 fruit jar in his possession not in service.

In the modification shown in Fig. 2, the parts which correspond to similar parts in Fig. 1 are designated by corresponding reference numerals. In this figure, however, the skirt is indicated by the reference numeral 22^a, and it will be observed that the waste-receiving receptacle 3 makes direct threaded engagement therewith, the inner 105 side of the skirt carrying a thread so that 110

the skirt itself is a threaded socket to receive the threaded upper end 19 of the waste-receiving receptacle 3. The threaded portion is indicated at 18^a. Here, again, a 5 packing gasket or washer 21 may be provided, if desired. In the particular form shown in Fig. 2 the thread is formed directly in the skirt 22^a by crimping the metal, although it will be understood that the particular manner of providing a thread or 10 equivalent means on the inside of the skirt is immaterial.

If desired, the lower part of the skirt may be weighted, so as to steady the stand on 15 the floor. Such a weight is indicated at 30 in Fig. 2, the same being in the form of a metal ring which is secured to the skirt in any desired manner, as by folding or crimping a portion of the skirt around said ring, 20 for example as indicated at 22^b, Fig. 2.

It is, of course, obvious that any suitable form of door or detachable closure might be provided, if desired, for the lower open 25 end of the skirt. Such a device is entirely supplemental. In Fig. 3 I have shown one conventional form of a removable closure plate for the open end of the skirt, said plate being indicated at 25. 26 is a lug at 30 one edge of said plate, the same being adapted to fit into a recess at the lower edge of the skirt, and 27 represents a latch on said plate adapted to engage the other edge of 35 said skirt.

By expanding the lower part of the skirt 35 a two-fold advantage is gained; first, it furnishes a broad base to rest on the floor or other support, and it also provides adequate room adjacent the lower end of the waste-receiving receptacle 3 whereby the same 40 may be firmly grasped by the hand to dislodge the same from its holding socket when it is desired to empty said receptacle.

I claim:

1. In a device of the character described, 45 an ash-receiving tray having a waste discharge outlet in the lower part thereof, a relatively long waste-conducting conduit depending therefrom, a skirt adjacent the lower end of said conduit forming a relatively enlarged cavity open at the lower end, and means for detachably connecting a waste-receiving receptacle within said cavity in position to receive waste falling through said conduit and to form a gas 50 tight joint, said receptacle being insertible and removable through the lower end of said skirt, said skirt forming a cavity of sufficient size to receive entirely within the same such a waste-receiving receptacle.

2. In a device of the character described, 55 an ash-receiving tray having a waste discharge outlet in the lower part thereof, a relatively long waste-conducting conduit depending therefrom, a skirt adjacent the lower end of said conduit forming a relatively

enlarged cavity open at the lower end, means for detachably connecting a waste-receiving receptacle within said cavity in position to receive waste falling through said conduit, said receptacle being 70 insertible and removable through the lower end of said skirt, said skirt forming a cavity of sufficient size to receive entirely within the same such a waste-receiving receptacle, and a waste-receiving receptacle. 75

3. In a device of the character described, an ash-receiving tray having a waste discharge outlet in the lower part thereof, a relatively long waste-conducting conduit depending therefrom, a skirt adjacent the 80 lower end of said conduit forming a relatively enlarged cavity open at the lower end, means for detachably connecting a waste-receiving receptacle within said cavity in position to receive waste falling through said 85 conduit, said receptacle being insertible and removable through the lower end of said skirt, said skirt forming a cavity of sufficient size to receive entirely within the same such a waste-receiving receptacle, and a waste-receiving receptacle, said waste-receiving receptacle having means for engagement with said means within said skirt for detachably securing the same within the cavity. 90

4. In a device of the character described, an ash-receiving tray having a waste discharge outlet in the lower part thereof, a relatively long waste-conducting conduit depending therefrom, a one-piece skirt adjacent the lower end of said conduit forming a 100 relatively enlarged cavity for wholly receiving within the same a waste-receiving receptacle insertible through the lower end of said skirt, and means within said cavity for detachably holding a waste-receiving receptacle therein in position to receive waste falling through said conduit. 105

5. In a device of the character described, an ash-receiving tray having a waste-discharge outlet in the lower part thereof, a relatively long waste-conducting conduit depending therefrom, a skirt connected to the lower part of said conduit and depending therefrom and forming a relatively enlarged cavity for wholly containing a waste-receiving receptacle insertible into said cavity through the lower end of said skirt, and means on the inner side of said skirt to hold such a receptacle in position to receive waste falling through said conduit. 115

6. In a device of the character described, an ash-receiving tray having a waste-discharge outlet in the lower part thereof, a relatively long waste-conducting conduit depending therefrom, a skirt rigidly connected to the lower part of said conduit and depending therefrom and forming a relatively enlarged cavity for wholly containing a waste-receiving receptacle insertible into said cavity through the lower end of said skirt, 120

and means on the inner side of said skirt to hold such a receptacle in position to receive waste falling through said conduit.

7. In a device of the character described, an ash-receiving tray having a waste-discharge outlet in the lower part thereof, a relatively long waste-conducting conduit depending therefrom, a skirt rigidly secured to the conduit adjacent its lower edge and forming a relatively enlarged cavity for receiving a waste-receiving receptacle in position to receive waste falling through said conduit, the upper part of said skirt forming a socket for directly receiving and holding the upper end of said waste-receiving receptacle, the latter being insertible and removable through the lower end of said skirt.

ROBERT G. FLEMING.
